(57) **CLAIM**

The ornamental design for a tray insert for drawers, as shown and described.

DESCRIPTION

FIG. 1 is a perspective view of a tray insert for drawers showing our new design;

FIG. 2 is a top plan view thereof;

FIG. 3 is a bottom plan view thereof;

FIG. 4 is a side elevational view thereof, the opposite side appearing as a mirror image; and,

FIG. 5 is an end elevational view thereof, the opposite end having an identical appearance.
